US00D902646S

(12) **United States Design Patent** (10) **Patent No.:** **US D902,646 S**
(45) **Date of Patent:** **** Nov. 24, 2020**

(54) **CONTAINER**

(71) Applicant: **YETI Coolers, LLC**, Austin, TX (US)

(72) Inventors: **Roy Joseph Seiders**, Austin, TX (US);
Matthew Joseph Petrillo, Austin, TX (US);
Kyle Ellison, Austin, TX (US)

(73) Assignee: **YETI Coolers, LLC**, Austin, TX (US)

(**) Term: **15 Years**

(21) Appl. No.: **29/674,592**

(22) Filed: **Dec. 21, 2018**

Related U.S. Application Data

(63) Continuation of application No. 29/606,307, filed on Jun. 2, 2017, now Pat. No. Des. 836,395.

(57)

CLAIM

The ornamental design for a container, as shown and described.

DESCRIPTION

FIG. 1 is a top, front, right perspective view of a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area represent unclaimed boundaries of the design. The broken lines depicting the remainder of the container show features that form no part of the claimed design.

1 Claim, 7 Drawing Sheets
